DEVICE FOR DEHAIRING ANIMAL HIDES AND PELTS

Filed July 26, 1948

UNITED STATES PATENT OFFICE

2,483,348

DEVICE FOR DEHAIRING ANIMAL HIDES
AND PELTSFrederic L. Newby and Richard F. Newby,
Anderson, Ind.

Application July 26, 1948, Serial No. 40,704

4 Claims. (Cl. 69—20)

1

This invention relates to a device for removing the hair from animal hides and pelts.

In the processing of hides or pelts, especially in preparation for the tanning process, it is first necessary to remove the coarse hair or fur covering the outside of the skin, without fracturing or marring the surface of the hide or pelt. This has generally been accomplished by chemical depilatories, or by large machines in which the whole hide or pelt is passed through a series of brushes and scrapers. In the first case the chemical process is time consuming and often harmful to the hide or pelt. In the second case, the mechanical handling and hair removing devices are generally not delicate enough, and because, by nature, the hides or pelts are of irregular shape and thickness, the skin surface is often marred and broken.

An object of the present invention is to provide a novel hair removing device which retains the delicate control of hand operation and at the same time makes possible the rate of production inherent in the application of mechanical power.

A further object of the invention is to provide a light weight hair removing device with which the operator may easily follow the irregularities of a hide or pelt without marring the surface thereof.

Still another object of the invention is to provide a hair removing device having means by which the relation of the shaving knives to the hide surface may be exactly regulated and kept constant, such setting being made in one operation.

A further object is to provide a de-hairing device in which the shaving knives may be quickly removed for grinding or replacement.

A further object is to provide a hair removing device in which the hood completely covers the revolving knives during the shaving operation, thus protecting the hands of the operator from injury, and also protecting the eyes of the operator from flying hair or foreign particles.

Another object is to provide a device in which said hood serves to stretch and hold firm a small portion of the hide so that it may be operated upon by the revolving knives.

Another object is to provide a portable hand tool for removing hair from animal hides or pelts which may be driven by any power means available, and embodying a hood or cover for the cutting elements, with a tubular extension on the hood or cover constituting a manipulating handle.

With the above and other objects in view, as will be presently understood, the invention consists in general of certain novel details of con-

2

struction and combinations of parts hereinafter fully described, illustrated in the accompanying drawings and particularly claimed.

In the accompanying drawings like characters of reference indicate like parts in the several views, and in which

Figure 1 is a longitudinal sectional view taken on the line 1—1 of Figure 2, showing all of the de-hairing mechanism within a protective hood,

10 Figure 2 is a bottom elevational view of the device showing the exposed cutters at the open end of the hood, and

Figure 3 is a cross-sectional view taken on the line 3—3 of Figure 1.

15 In the present invention there is provided a tubular handle 5 at the lower end of which is a hood comprising a conical section 6 extending from the tubular handle 5 and terminating in a cylindrical portion 7. A sleeve 8 is longitudinally 20 adjustably mounted within the tubular handle 5 in proximity to the conical portion 6 of the hood and is retained in adjusted position by the set screw 9 threaded through the handle for engagement with said sleeve, as shown in Fig. 1.

25 In turn, there is journaled in the sleeve 8 a shaft 10, said shaft revolving in the sleeve on the standard bearing assembly shown by dotted lines in Fig. 1. The inner end of shaft 10 is threaded as at 11 for receiving the rotatable flexible shaft 30 12, which is locked on the shaft by the set screw 13, and which flexible shaft is in communication with a power source. Immediately below this threaded portion 11 is a removable collar 14 locked in place on the shaft by the set screw 15, for 35 retaining the shaft 10 in journaled relation to its bearings.

The outer end of the shaft 10 extends beyond the sleeve 8 and into the hood and is threaded as at 16. The threaded portion 16 of the shaft 10 40 adjacent the outer end of the sleeve 8 is flattened on opposite sides for a short distance as at 17 to serve as a wrench hold when positioning the collar 14 on the threaded portion 11 of the shaft.

On the inner portion of the threads 16 is adjustably positioned a nut 18 which serves to lock the shaving assembly on the threaded portion 16 of the shaft 10.

On the outer threaded end 16 of the shaft 10 is threaded a sleeve 20 having an outwardly 50 directed annular flange portion 21. An outer sleeve 22 is mounted on the sleeve 20 and has an outwardly directed annular flange 23 overlying and contacting the aforesaid flange 21. Immediately below the flange portion 21 is a disc shaped head 24 secured to said flange 21 by the screws 55 25 and having equally spaced, arcuate lugs 26

projecting from its outer face and through which said screws pass. These lugs serve as positioners for the shaving knives 27 and also as additional support against lateral movement of said knives. Projecting inwardly from the inner face of the head 24 are equally spaced, arcuate lugs 28 which are seated in similarly shaped recesses 29 in the flange portion 21 of the sleeve 20, and shown in Figures 1 and 3. These lugs 28 assist the screws 25 in resisting the torque stresses between the head 24 and flange portion 21 of the sleeve 20.

The knives 27 are placed equidistantly and radially on the head 24 so that the cutting edges 30 are lined up with the axis of revolution of the shaving assembly, as shown in Fig. 2. Each of the knives 27 is attached to the head 24 and the flange portion 21 of the sleeve 20 by two screws 31, placed near either end of the knife. The outer screw in each blade is extended through the sleeve 20 and threadedly engaged in the flange portion 23 of the sleeve 22 to hold said sleeve in position in relation to the sleeve 20.

Each knife 27 consists of a bar-like blade of uniform cross-section, having a thickened leading edge, the leading face being ground slightly concave as at 32a and the underside nearest the cutting edge also being made slightly concave as at 32, thus more clearly defining the cutting edge 30.

In using the device the operator grasps the tubular handle 5 and places the outer peripheral edge of the hood on the stretched hide or pelt. The relation of the knives to the hide surface may then be quickly adjusted by moving the sleeve 8 within the handle and locking it in position by the set screw 9. Any available power means is then applied to the remote end of the flexible shaft 12, causing the knife assembly to rotate at any set speed. The device is then maintained in a vertical position and then moved horizontally over the surface of the hide, the relation between the knives and hide surface being maintained at a constant distance by the hood.

It is apparent that the device may easily follow the irregularities and contours of the hide, and may be applied to any one spot for as long or short a period as is necessary for removing the hair, thus using to full advantage the skill and judgement of a trained operator.

It is apparent also that the hood completely covers the knives during the shaving process and completely protects the hands of the operator from the cutting tool and his eyes from flying particles of hair or any accompanying foreign matter. In addition the circular edge of the hood serves to stretch and hold firm that portion of the hide or pelt within range of the revolving knives. Still another advantage of the device is that at no time is it possible for the operator to inadvertently groove or injure the surface of the hide or pelt with the sharp end points of the shaving knives, since said knives do not extend below the plane of the marginal edges of the hood.

While there are shown herein and described the preferred embodiment of the invention, it is nevertheless to be understood that minor changes may be made therein without departing from the spirit and scope of the invention as claimed.

What is claimed is:

1. A portable de-hairing device comprising a rotatable cutter head, an open ended hood surrounding the cutter head, a tubular handle extending inwardly from the hood, a bearing shaft journalled in said handle and connected to said

cutter head and a remotely powered flexible drive shaft for said bearing shaft and cutter head, said cutter head including a sleeve secured to the outer end of the bearing shaft, an outwardly directed annular flange on the outer end of the sleeve, a disc head interfittingly anchored to said flange and radial cutter blades secured to the outer face of the disc head.

2. A portable de-hairing device comprising a rotatable cutter head, an open ended hood surrounding the cutter head, a tubular handle extending inwardly from the hood, a bearing shaft journalled in said handle and connected to said cutter head and a remotely powered flexible drive shaft for said bearing shaft and cutter head, said bearing shaft being longitudinally adjustable in said handle to position the effective end of the cutter head in proper relation to the open end of the hood, said cutter head including a sleeve secured to the outer end of the bearing shaft, an outwardly directed annular flange on the outer end of the sleeve, a disc head interfittingly anchored to said flange and radial cutter blades secured to the outer face of the disc head.

3. A portable de-hairing device comprising a rotatable cutter head, an open ended hood surrounding the cutter head, a tubular handle extending inwardly from the hood, a bearing shaft journalled in said handle and connected to said cutter head and a remotely powered flexible drive shaft for said bearing shaft and cutter head, said cutter head including a sleeve secured to the outer end of the bearing shaft, an outwardly directed annular flange on the outer end of the sleeve, a disc head interfittingly anchored to said flange and radial cutter blades secured to the outer face of the disc head, and lugs projecting from the outer face of the disc head constituting abutments for the cutter blades.

4. A portable de-hairing device comprising a rotatable cutter head, an open ended hood surrounding the cutter head, a tubular handle extending inwardly from the hood, a bearing shaft journalled in said handle and connected to said cutter head and a remotely powered flexible drive shaft for said bearing shaft and cutter head, said bearing shaft being longitudinally adjustable in said handle to position the effective end of the cutter head in proper relation to the open end of the hood, said cutter head including a sleeve secured to the outer end of the bearing shaft, an outwardly directed annular flange on the outer end of the sleeve, a disc head interfittingly anchored to said flange and radial cutter blades secured to the outer face of the disc head, and lugs projecting from the outer face of the disc head constituting abutments for the cutter blades.

Certificate of Correction

Patent No. 2,483,348

September 27, 1949

FREDERIC L. NEWBY ET AL.

It is hereby certified that error appears in the printed specification of the above numbered patent requiring correction as follows:

**Column 1, line 7, for the word "hole" read *hide*;
and that the said Letters Patent should be read with this correction therein that
the same may conform to the record of the case in the Patent Office.**

Signed and sealed this 31st day of January, A. D. 1950.
